RECIPROCATING MOPHEAD CLEANER

Eugene Autry, Brooklyn, N. Y.

Application May 29, 1946, Serial No. 672,920

4 Claims. (Cl. 15—88)

This invention relates to a sanitary cleaning device for dust mops and has for its primary object to provide an apparatus capable of being placed in a dust proof bag and to engage the head of a mop while thus disposed for cleaning the dust therefrom in such a manner that the dust will be collected in the bottom of the bag.

More particularly, it is a primary object of the present invention to provide a cleaner of the above described character capable of being operated by a reciprocating motion for effectively extracting the dust from the mop while the device, with the mop head attached thereto, is disposed in a dust proof bag.

Other objects and advantages of the invention will hereinafter become more fully apparent from the following description of the drawings, which illustrate a preferred embodiment thereof, and wherein:

Figure 1 is a longitudinal, substantially central sectional view showing the cleaner with the beater in a projected position;

Figure 2 is a similar view showing the beater in a partially retracted position;

Figure 3 is a top plan view, partly broken away, of the device;

Figure 4 is a cross-sectional view thereof, taken substantially along a plane as indicated by the line D—D of Figure 2;

Figure 5 is a top plan view, partly broken away and showing the cleaner in an operative position;

Figure 6 is a fragmentary sectional view showing the handle engaging clip of the beater;

Figure 7 is a similar view showing the mop head engaging clip thereof, and

Figure 8 is a side elevational view, partly broken away, showing the mop cleaner disposed in a dust receiving bag and containing a mop to be cleaned.

Referring more specifically to the drawings, the mop cleaner in its entirety is designated generally A and includes a frame having four bars 1 which are channel shape in cross-section and arranged to open inwardly. The bars 1 are connected at their lower ends to the periphery of a disk 8 having a central hub 18. The upper ends of the channel bars 1 are connected to the upturned annular flange 19 of a top plate 17 which is provided with an upstanding handle 10 on its outer side.

A tube 7 is fixedly disposed adjacent its upper end in the hub 18 and is provided with a threaded cap 9 which is removably mounted on its lower

end. A beater head 2 is slidably guided by the bars 1 for reciprocating motion toward and away from the top plate 17. As best seen in Figure 4, the beater head 2 includes a solid central portion 20 having four, equally spaced outwardly projecting arms 21 which have outwardly diverging side edges and each of which is provided with a lug 11 which extends from the outer edge thereof. Each of the lugs 11 slidably engages one of the channel bars 1 so that the four lugs 11 through slidable engagement with the four channel bars 1 slidably guide the beater head 2.

A rod 3 has its upper end anchored in the central portion of the beater head 2 and extends downwardly therefrom and into the tube 7 in which said rod is reciprocally disposed. An expansion coiled spring 4 is mounted on the rod 3 and has its lower end bearing against the tube 7 and its upper end engaging the under side of the beater head 2 for urging said head upwardly and toward the top plate 17. An annular weight or collar 5 is slidably mounted on the tube 7 between the hub 18 and the cap 9 and is connected to the beater head 2 by connecting rods 6.

The top plate 17 supports two diametrically spaced fasteners, designated generally 22 and 23, as best seen in Figures 5, 6, 7 and 8. The fasteners 22 and 23 are mounted on the under side of the plate 17 and each include a hinge section 12 which is fastened to the plate 17. The fastener 22 is also provided with a hinge section 24 which is pivotally connected to its associated hinge section 12 and which is provided with a downwardly offset intermediate portion 25 and a turned back free end 26 which is disposed at an acute angle to the intermediate portion 25 and which is adapted to resiliently engage a correspondingly disposed free end of a spring clip 13, which is fastened to the underside of the plate 17 and which functions to releasably retain the hinge section 24 in an operative position against the underside of the plate 17. The fastener 23 is provided with a swingably mounted hinge section 27 having a free end 28, corresponding to the end 26 for engaging a spring latch 13 of the fastener 23 in the same manner and for the same purpose. The hinge section 27 is provided with an arcuate intermediate portion 29 adapted to engage a mop handle 16 adjacent the mop head 30 thereof for supporting the mop handle 16 against the underside of the plate 17. The downwardly offset intermediate portion 25 of the fastener 22 is adapted to engage and clamp the mop head 30 adjacent its free end to the underside

50 55

of the plate 17 for thus supporting the mop head 30 between the plate 17 and the beater head 2.

The mop cleaner A with the mop head 30 thus clamped therein is inserted into a dust proof bag 14 and the mouth of the bag is secured around the flange 19 by a cord 15. The bag 14 is provided with an opening 31 adjacent its mouth and through which the handle 16 extends.

With the cleaner and mop thus disposed in the bag 14, as illustrated in Figure 8, the operator grasps the handle 16 and by an up and down movement will cause the beater head 2 to be reciprocated toward and away from the top plate 17 for beating the dust from the mop head 30 so that the dust will be deposited in the bag 14. On the upward movement of this up and down movement, gravity pull combined with the weight 5 will cause the piston 2 and rod 3 to slide downwardly thereby compressing the spring 4. By a sudden reversal of the direction of movement to a downward movement, the frame will be caused to move suddenly in the opposite direction thereby allowing the spring 4 to react and drive the beater head 2 toward the plate 17 and into engagement with the mop head 30 for beating the dust therefrom. It will be readily apparent that by repeating this operation dust can be quickly extracted from the mop head.

Various modifications and changes are contemplated and may obviously be resorted to without departing from the spirit and scope of the invention as hereinafter defined by the appended claims.

I claim:

1. A mop cleaner comprising an elongated open frame having a plate at one end thereof and a guide projecting from its opposite end, a beater head reciprocally mounted in said frame and having means projecting therefrom and reciprocally engaging said guide, means mounted on the underside of said plate for detachably supporting a mop head between the frame plate and beater head, and a handle on the opposite side of the frame plate by which the mop cleaner is adapted to be manually supported and reciprocated for moving the beater head into and out of engagement with the mop head, said frame including spaced longitudinally disposed bars forming the sides thereof, said bars being channel shaped in cross-section and having legs extending inwardly of the frame, and lugs projecting outwardly from the beater head and slidably engaging the channel portions of said bars.

2. A mop cleaner comprising an elongated open frame having a plate at one end thereof and a guide projecting from its opposite end, a beater head reciprocally mounted in said frame and having means projecting therefrom and reciprocally engaging said guide, means mounted on the underside of said plate for detachably supporting a mop head between the frame plate and beater head, and a handle on the opposite side of the frame plate by which the mop cleaner is adapted to be manually supported and reciprocated for moving the beater head into and out of engagement with the mop head, said means for engaging the guide including a rod projecting from the beater head and in telescopic

engagement with said guide, an annular weight slidably mounted on said guide, and rods connecting said weight to the underside of the beater head.

3. A mop cleaner comprising an elongated open frame having a plate at one end thereof and a guide projecting from its opposite end, a beater head reciprocally mounted in said frame and having means projecting therefrom and reciprocally engaging said guide, means mounted on the underside of said plate for detachably supporting a mop head between the frame plate and beater head, and a handle on the opposite side of the frame plate by which the mop cleaner is adapted to be manually supported and reciprocated for moving the beater head into and out of engagement with the mop head, said means for engaging the guide including a rod projecting from the beater head and in telescopic engagement with said guide, an annular weight slidably mounted on said guide, rods connecting said weight to the underside of the beater head, whereby the weight will urge the beater head in a direction away from the frame plate, and an expansion coiled spring carried by said first mentioned rod and interposed between the beater head and the adjacent end of said guide.

4. In combination, an elongated open frame having a plate at one end thereof, means mounted on the under side of said plate for detachably supporting a mop head thereagainst, said frame including a guide structure, a beater head reciprocally engaging in the guide structure and guided thereby for movement toward and away from the side of said frame plate on which the mop head is disposed, spring means bearing against the opposite end of the frame and the beater head and urging the beater head toward the frame plate and into engagement with the mop head supporting means, a handle mounted on the opposite side of the frame plate and by means of which the frame is adapted to be manually supported and reciprocated for moving the beater head toward and away from the frame plate and mop head, and a bag detachably disposed over the frame and having the mouth thereof secured to the frame plate and in which the dust from the mop head is adapted to be deposited when the frame is manually reciprocated.
